(No Model.)

F. MEDART.
Balance Swing.

No. 239,970.

Patented April 12, 1881.

ATTEST:

Eugene Wolf
F. Medart

INVENTOR:

Friedrich Medart

UNITED STATES PATENT OFFICE.

FREDRICK MEDART, OF ST. LOUIS, MISSOURI.

BALANCE-SWING.

SPECIFICATION forming part of Letters Patent No. 239,970, dated April 12, 1881.

Application filed December 9, 1880. (No model.)

To all whom it may concern:

Be it known that I, FREDRICK MEDART, a citizen of the United States, residing at St. Louis, in the State of Missouri, have invented 5 certain new and useful Improvements in Balance-Swings; and I do hereby declare that the following is a full, clear, and exact description of the invention, reference being had to the accompanying drawing, and to the letters of reference marked thereon, forming a part of this specification.

This invention relates to certain improvements in balance-swings used as an exercising apparatus for children; and this invention consists in constructing such apparatus with a central tubular iron post attached to a cast-iron base, the swing-frame being pivoted on a cross-arm that is made vertically adjustable on the supporting-post by means of a pin and 20 series of adjusting-holes in said post.

The drawing is a perspective view illustrating my invention.

A is the swing-frame, pivoted at its center to the cross-arm B, which has a central sleeve 25 portion, b, surrounding the post C, and made vertically adjustable on the same by means of a pin, c, engaging in one of a series of adjusting-holes, c', as shown. The frame A is properly tied together and provided with handles 30 a at each end, as shown.

The post C is fixedly secured in the central socket of the base D in any suitable manner, and in my preferred construction this post is formed of gas-pipe; yet in some cases wood 35 may be substituted therefor without departing from the spirit of my invention.

The cast-iron supporting-base D is formed, as shown, with radial bracing wings or feet d, the outer ends of which are faced with a facing, 40 d', of leather, &c., to prevent slipping of the apparatus upon the floor when in use.

In moving the apparatus from point to point the swing-frame A will be let down to the base, and the pin c inserted over the sleeve through the hole c', when the apparatus can be transported by the handles a a to any desired point. 45

My improved apparatus is light, durable, and convenient, and by its means the adjustment of the swing-frame to any desired elevation is easily and readily accomplished. 50

Having thus fully described my said invention, what I claim as new, and desire to secure by Letters Patent, is—

1. A balance-swing exercising apparatus, when provided with a single central supporting-post, C, as described, and for the purpose set forth. 55

2. A base, D, for balance-swings, formed of cast-iron, and provided with radial bracing feet or wings d, as described, and for the purpose set forth. 60

3. The base D of a balance swing exercising apparatus, having its feet d provided with a facing, d', of leather, &c., as described, and for the purpose set forth. 65

4. A balance-swing exercising apparatus formed with a central supporting-post, C, having adjusting-holes c' and pin c, base D, cross-arms B, having a sleeve portion, b, and a swing-frame, A, substantially as and for the purpose set forth. 70

5. A balance-swing exercising apparatus, when provided with a hole, c', through its central supporting-post, C, as described, and for the purpose set forth. 75

Signed at St. Louis, in the State of Missouri, this 2d day of December, 1880.

FREDRICK MEDART.

In presence of—

EUGENE WOLF,
WM. MEDART.
